UNITED STATES PATENT OFFICE.

ARTHUR E. DOWELL, OF WASHINGTON, DISTRICT OF COLUMBIA, ASSIGNOR TO THE DUPLEX PRINTING PRESS COMPANY, OF BATTLE CREEK, MICHIGAN.

PRINTING-PRESS.

SPECIFICATION forming part of Letters Patent No. 694,846, dated March 4, 1902.

Application filed September 20, 1901. Serial No. 75,842. (No model.)

To all whom it may concern:

Be it known that I, ARTHUR E. DOWELL, of Washington, District of Columbia, have invented certain new and useful Improvements 5 in Printing-Presses; and I hereby declare that the following is a full, clear, and exact description thereof, reference being had to the accompanying drawings, which form part of this specification.

This invention is an improvement in web-looping mechanism of web-handling machinery, and is especially designed for use in connection with machines wherein a portion of an otherwise continuously-moving web is 10 intermittently stopped, such stoppage of the web being effected by movable looping-rollers; and the object of the present invention is to so control or regulate the movement of the looping-rollers by, from, or with the movement of the web feeding, forwarding, or delivering rolls that the web will be looped by the rollers exactly in a predetermined ratio proportionate to the speed of the feeding-rolls, and hence by varying the speed of the feeding-rolls the action of the looping-rollers will be 15 correspondingly and proportionately varied.

The invention is particularly applicable to what are known as "duplex" flat type-bed web-perfecting presses, and in the accompanying drawings I have illustrated the invention as adapted for and applied to such a press; but the invention is applicable to other web-printing presses or web-operating mechanism; and it consists, essentially, in the combinations and constructions of parts summarized in the claims.

Referring to the accompanying drawings, Figure 1 is a detail vertical sectional elevation of the web feeding, looping, delivering, and cutting mechanism of a duplex web-perfecting press equipped with my invention. Fig. 2 is a detail section on line 2 2, Fig. 4, showing the device for operating the looping-rollers from the shaft of one of the delivery-rolls. Figs. 3 and 4 are detail sectional views, respectively, taken on line 3 3 and line 4 4, Fig. 1. Fig. 5 is a detail side elevation of the press, showing the changeable-speed drive mechanism of the rolls; and Figs. 6 and 7 are 20 detail side and plan views of a modification of the looping-roller-operating device.

K K' K² designate the web infeed-rolls, and O O' the outfeed or delivery rolls, driven at an uniform relative peripheral speed by a connecting train of gears o o, as indicated in the drawings. l l' designate lower and upper web-looping rollers mounted in a vertically-reciprocating frame L, and M M' designate web-guiding rollers, C C' cutting-cylinders, and W the web. All said parts are arranged and operated substantially as described in Cox's patent, No. 478,503, of July 5, 1892.

The feed-rolls K may be driven by a train of gears k k' k² from a gear k³ on the main shaft of the machine. To enable variable speeds to be imparted to the feed-rolls, the gears k k' may be made removable and interchangeable with various-sized gears, and the gear k' may be journaled upon a swinging lever P, pivoted on the shaft of gear k³ and adjustable toward or from the gear k by means of a screw P', as indicated in Fig. 5, or any other convenient or preferred means may be used by which different speeds may be imparted to the feed-rolls. The cutting-cylinders C C' may be driven at an uniform speed by the train of gears o² o³ o⁴ o⁵ from the same or a like gear k³ on the main shaft, as indicated in Fig. 1.

As shown in Figs. 1 to 4, the frame L has a rack extension L' at its upper end, which meshes with a small gear R, which may be mounted on a shaft of its own and driven from the feed or delivery rolls, but can be, as shown, very conveniently mounted upon and loosely journaled on the shaft O⁴ of the delivery-roll O. Said gear R, as shown, is half the diameter of the roll O, so that when it is actuated it will move the frame L at exactly half the speed at which the periphery of the roll is moving. The gear R should be locked to the shaft only during the time when it is desired to cause the rollers l l' to rise and intermittently stop the web, and this may be effected by any suitable device. For example, the gear R may be provided with a clutch-face R' on one end opposite a clutch-block r, splined on the shaft of roll O and moved toward or from the gear R by means of a bifurcated lever S, pivoted on a bracket S' and having a rearwardly-projecting arm S², carrying a friction-roller s, which traverses the

groove s^2 of a drunken cam s' , which should be driven independently of the delivery-rolls. As shown, cam s' is fixed on the shaft of the cutting-cylinder C. The cam s' is shown as 5 a single-throw cam, and by this construction the gear R will be locked to the feed-roll shaft during every other half-revolution of the cam s' or cutting-cylinder C and unlocked therefrom during the alternate half-revolu- 10 tions regardless of the speed of the feed and delivery rolls. Obviously the times and relative extent of time during which gear R is locked to the delivery-roll shaft or unlocked therefrom can be varied by properly design- 15 ing the cam s' ; but for ease of explanation it may be assumed, for example, that in the operation of the press, as shown, the part of the web in the printing mechanisms (which are beyond the rollers M M', as shown in the Cox 20 patent) is stopped during the time of a half-revolution of the cam s' (or cutting-cylinders) and then fed forward thereafter about as explained in said patent. With this assumption it will be readily understood that if the 25 feeding and delivery rolls are turning through forty inches of web during each rotation of the cam s' or the cutting-cylinders then the looping-rollers should and will be raised ten inches by gear R and rack L' during the time 30 gear R is locked to the shaft of roll O, during which time the printing is effected. Consequently the lower looping-roller l would take up the twenty inches of web fed in by the feed-rolls, and the upper looping-roller l' 35 would give out a like amount of web as demanded by the delivery-rolls. If, however, it is desired to print sheets of another length, the speed of the feed and delivery rolls can be altered by substituting another gear k 40 (either larger or smaller, as required) for the gear k used when forty inches of web are fed, and supposing that the length of sheet to be printed was to be twenty inches instead of forty a smaller gear k (of the proper diameter) would be substituted; but the cam s' must still be driven at the same speed, and in the construction shown the cutting-cylinders C C' would also be always uniformly 45 driven. By thus changing gear k the feed 50 and delivery rolls would be slowed down so that they would only feed through twenty inches of web for each rotation of cam s' and the cutting-cylinders, and in so doing they would rotate at just half the peripheral speed 55 at which they rotated when feeding forty inches of web, and consequently during the time the gear R is locked to the shaft of roll O by the action of cam s' the looping-rollers l l' would be raised but five inches. Hence the 60 lower looping-roller l would just take up the ten inches of web fed in during the impression of the feed-rolls and the upper looping-roller l' would just give out the like amount demanded by the delivery-roll. As the web 65 is fed freely between the cutting-cylinders and the latter rotate at an uniform speed, they will act to properly sever sheets of dif-

ferent lengths, the length of sheet depending entirely upon the amount of web fed between the cutting-rolls by the delivery-rolls, whether 70 the latter be speeded high or low. Therefore in order to enable the machine to operate upon or produce different lengths of sheets in the web it is only necessary to substitute the proper interchangeable gears $k k'$ or otherwise properly vary the peripheral speed of the feed and delivery rolls as desired, so that they will operate to feed only the proper length of web in a given time—i. e., say one revolution of the cam s' . As soon as gear R 80 is released from the shaft O⁴ the looping-frame L descends, so that the collected loop of web is transferred from the roller l to roller l'. The frame may descend by gravity, but is preferably aided in its descent by any suitable or preferred means. As shown, a spring-pressed lever T bears upon a friction-roller L² on the lower end of frame L, the spring T' being adjusted so as to insure the proper and full descent of the looping-frame, and thereby 90 cause the looping-roller l to draw the web from the lower to the upper loop, substantially as described in said Cox patent. To prevent too-sudden stoppage or descent of the looping-rolls l l', dash-pot or air-cylinder U may be 95 arranged below the frame L and the piston u thereof attached to the lower end of said frame, as shown.

In the modification shown in Figs. 6 and 7 (which is but one of many that will or might 100 occur to a skilled mechanic when the invention is once understood) a frictional gear V is secured to the shaft O⁴ of roll O, and a friction-bar L³ is attached to the upper end of looping-frame L. At the proper time this 105 friction-bar is held against the gear V by means of a roller v on the pivoted lever X, which is actuated by a spring X', as shown, and when bar L³ is so pressed against the friction-gear V the looping-frame will be raised. 110 As shown, the bar L³ is released at the proper time by means of a cam s⁴ on the shaft of the lower cutting-cylinder C. In practice the cam might be arranged to hold the bar L³ against the gear V and the spring arranged 115 to release the bar. The practical operation of the parts shown in Figs. 6 and 7 is substantially the same as those previously described.

The invention is of course adapted to operate one or more looping-rollers simultaneously and to operate either a web take-up or a web give-up looping-roller.

By the present invention the necessity for nicely adjusted and calculated cams for operating the looping-rollers is dispensed with. The same mechanism can be used to operate the looping-rollers to take up any length of web, and when used in a web-printing press it enables the same press to be readily employed to operate upon and produce sheets of different lengths by simply regulating the speed of the feeding and delivering rollers. As applied to web-machines generally the extent

of movement of the looping-rollers, relative or proportionate, to the extent of peripheral movement of the web-rolls in a given time can be determined by the relative diameters 5 of the gear R (or V) and the web-roll; but when once determined the proportionate speeds of movement of the looping-rollers and feed-rolls remains unchanged, and when the speed of the web-rolls is changed the extent 10 of movement of the looping-rollers will also change exactly in accordance with the extent of rotation of the web-roll during the time the gear R (or V) is caused to positively operate the looping-frame.

15 Having thus described my invention, what I therefore claim as new, and desire to secure by Letters Patent thereon, is—

1. The combination of a continuously-operating web-forwarding roll, a web-looper, 20 and mechanism for intermittently actuating the looper during a part of the revolution of said roll, said mechanism being adapted to move the looper at a predetermined speed always uniformly proportionate to the peripheral speed of said roll, substantially as described. 25

2. The combination of a web-actuating roll, means for changing the speed of the web-roll, a web-looper, a gear for operating said looper, 30 and mechanism for causing the gear to intermittently move the looper, during a part of the revolution of the roll, at a predetermined speed proportionate to the peripheral speed of the said roll, substantially as described.

3. The combination of the web-feed roll driven at an uniform speed, means for changing the speed of said roll, a looping-frame, a gear for operating said looping-frame actuated from and driven uniformly with relation 40 to said web-roll, and mechanism for causing the gear to move the frame during a predetermined part of the revolution of the web-roll, and at a rate of movement proportionate to the peripheral speed of the web-roll, substantially as described. 45

4. The combination of a continuously-driven web-roll, a gear actuated thereby, a looper-frame adapted to be intermittently moved by said gear, and an uniformly-driven 50 cam and mechanism controlled by the cam for causing the gear to actuate the frame during a predetermined part of the revolution of the cam, substantially as described.

5. The combination of a web-feed roll and 55 means for varying the speed thereof, a gear adapted to be driven uniformly with the feed-roll, a web-looping frame adapted to be intermittently operated by said gear, and an uniformly-operating cam and mechanism controlled by said cam adapted to cause the gear to actuate the frame during a predetermined part of the revolution of the cam, substantially as described.

6. The combination of an uniformly-driven 65 and continuously-operating web-roll, a gear adapted to be driven uniformly with relation to said roll a looping-roller frame, and a bar

thereon adapted to be actuated by said gear; with means for causing said gear to actuate said bar during some part of the revolution 70 of the roll, substantially as described.

7. The combination of a continuously-driven web-roll, means for varying its speed, a gear on the shaft thereof; and a looping-frame adapted to be operated one way by said 75 gear; with a continuously and uniformly driven cam, and mechanism, controlled by said cam, whereby said gear is caused to move the looping-frame during a predetermined part of the revolution of the cam, substantially 80 as described.

8. The combination of a web-feed roll, a gear operated therewith, a looping-roller, a reciprocating frame carrying said roller, and a bar attached to said frame and engaging said 85 gear; with means for causing said gear to intermittently operate the bar, and means for returning said frame to its original position when permitted by the gear, substantially as described. 90

9. The combination of the changeable-speed web-rolls, a gear adapted to be operated intermittently and uniformly with the rolls, and a looping-frame adapted to be operated by said gear; with a cam, and mechanism operated 95 thereby, whereby said gear is caused to actuate the looping-frame, during a part of the revolution of the cam, and irrespective of the speed of the feed-rolls, substantially as and for the purpose described. 100

10. The combination of a changeable-speed web-feeding roll, a gear operated therefrom, an uniformly-driven cam, a looping-frame adapted to be intermittently operated by said gear, and means controlled by said cam whereby the gear is caused to actuate the frame during part of the revolution of the cam, substantially as described. 105

11. The combination of continuously and synchronously driven web feed and delivery 110 rolls, a gear on one roll-shaft, a pair of uniformly-driven cutting-cylinders, a cam on one cylinder-shaft, a frame carrying web-looping rollers, and an arm on said frame adapted to engage said gear; with mechanism controlled 115 by the said cam, adapted to cause the gear to operate the frame during a predetermined part of the revolution of the cutting-cylinders, and means for varying the speed of the feed-rolls, substantially as described. 120

12. The combination of a continuously-operating web-feed roll, a gear actuated thereby and adapted to be driven uniformly therewith, a frame carrying a looping-roller, a bar connected to said frame and engaging said 125 gear, and means for causing said gear to intermittently operate the bar, substantially as described.

13. The combination of a web-feeding roll, a loose gear on the shaft thereof, a frame carrying a web-looper, adapted to be operated by said gear, and means for causing said gear to rotate with the roll, substantially as described. 130

14. The combination of a web-feeding roll, a gear on the shaft thereof, a frame carrying a looping-roller, a rack-bar connected to said frame and meshing with said gear, and means for intermittently locking said gear to the roll, substantially as described.

15. The combination of a changeable-speed web-roll, a gear on the shaft thereof, a cam, and means controlled by the cam for locking said gear to the roll during some part of the revolution of the cam; with a looping-roller, a reciprocating frame guiding said roller, and a rack-bar attached to said frame engaging said gear, substantially as described.

16. The combination of a web-roll, a gear on the shaft thereof, means for locking said gear to said roll during some part of the revolution thereof, a looping-frame, and a bar attached to said frame engaging said gear; with means for returning said frame to its original position when the gear is released from the roll, substantially as described.

17. The combination of a changeable-speed web-feeding roll, a gear on the shaft thereof, an uniformly-rotated cam, means controlled by the cam for locking said gear to the roll during some part of the revolution thereof, a looping-roller, a reciprocating frame guiding said roller, and a rack-bar attached to said frame and meshing with said gear; and means for returning said frame to its original when the gear is released from the roll, substantially as described.

18. The combination of continuously and synchronously rotating web-feeding rolls; a gear on one roll-shaft, uniformly-rotating cutting-cylinders, a cam on the shaft of one cutting-cylinder, a looping-frame adapted to be operated by the gear on the roll-shaft, and mechanism controlled by the cam on the cutting-cylinder shaft, for causing said gear to actuate said frame during a predetermined part of the revolution of the cutting-cylinders, substantially as described.

19. The combination of the continuously-driven web-roll, means for varying the speed thereof, and a gear on the shaft thereof; a continuously and uniformly driven cutting-cylinder, a cam on the shaft thereof, and a looping-frame having a bar adapted to engage said gear; with mechanism, controlled by said cam, whereby said gear and bar are caused to move the looping-frame during a predetermined part of the revolution of the cutting-cylinder, substantially as described.

20. The combination of the continuously and synchronously driven feed-rolls, a gear on one roll-shaft, means for varying the speed of said rolls; continuously and uniformly driven cutting-cylinders, and a cam on one cylinder-shaft; with a looping-frame, a bar thereon adapted to engage said gear, and mechanism substantially as described controlled by said cam, whereby said gear and arm intermittently move the looping-frame during a predetermined part of the revolution of the cutting-cylinders, irrespective of

the speed of the feed-rolls, substantially as described.

21. The combination of the changeable-speed web-rolls, a loose gear on the shaft of one of the rolls, a clutch for locking said gear to said roll, a lever for operating said clutch, and an uniformly-rotating cam for operating said clutch-lever; with a looping-frame, a bar attached thereto engaging said gear, and means for returning said looping-frame to normal position when said gear is released from the roll, substantially as described.

22. The combination of the web-rolls, the cutting-cylinders, a gear on one web-roll shaft, a clutch for locking said gear to said roll, a lever for operating said clutch; and a cam on one cutting-roll shaft for operating said lever; with a looping-frame adapted to be operated by said gear, and means for returning said looping-frame to normal position when said gear is released from the roll, substantially as described.

23. The combination of variable-speed web-rolls, and uniformly-driven cutting-cylinders, a gear on the shaft of one of the web-rolls, a clutch for locking said gear to said roll, a lever for operating said clutch, and a cam on one cutting-roll shaft for operating said lever; with a looping-frame and a bar attached thereto meshing with said gear, and means for returning said looping-frame to normal position when said gear is released from the roll, substantially as described.

24. The combination of the synchronously-driven web feed and delivery rolls, means for varying the speed of said rolls, the uniformly-driven cutting-cylinders, a gear on the shaft of one of the delivery-rolls, a clutch for locking said gear to said roll, a lever for operating said clutch, and a cam, on one cutting-roll shaft, for operating said lever; with a looping-frame, a rack-bar attached thereto and meshing with said gear, and means for returning said looping-frame to normal position when said gear is released from the roll, substantially as described.

25. The combination of a web-feed roll and means for varying the speed thereof, a gear adapted to be driven uniformly with the feed-roll, a web-looping frame adapted to be intermittently operated by said gear, and mechanism adapted to cause the gear to actuate the frame during a predetermined part of the revolution of the feed-roll, substantially as described.

26. The combination of a continuously-driven web-roll, means for varying its speed, a gear adapted to be operated therewith; and a looping-frame adapted to be operated one way by said gear; with a cam, and mechanism, controlled by said cam, whereby said gear is caused to move the looping-frame during a predetermined part of the revolution of the cam, substantially as described.

27. The combination of continuously-driven web feed and delivery rolls, a gear adapted to be operated therewith, a pair of cutting-cyl-

5 inders, a cam, and a frame carrying a web-looping roller and adapted to engage said gear; with mechanism controlled by the said cam, adapted to cause the gear to operate the frame during a predetermined part of the revolution of the cutting-cylinders, substantially as described.

28. The combination of a changeable-speed web-feeding roll, a gear driven therefrom, a 10 cam, means controlled by the cam for driving said gear from the roll during some part of the revolution thereof, a looping-roller, a reciprocating frame guiding said roller, adapted to be operated by said gear; and means 15 for returning said frame to its original position when the gear is released from the roll, substantially as described.

29. The combination of continuously and synchronously rotating web-feeding rolls; a 20 gear driven from said rolls, uniformly-rotating cutting-cylinders, a cam, a looping-frame adapted to be operated by said gear, and mechanism controlled by the cam for causing said gear to actuate said frame during a predetermined part of the revolution of the cutting-cylinders, substantially as described.

25 30. The combination of the continuously-driven web-roll, means for varying the speed

thereof, and a gear adapted to be driven therewith, continuously-operating cutting-cylinders, a cam, and a looping-frame adapted to be operated by said gear; with mechanism, controlled by said cam, whereby said gear is caused to move the looping-frame during a predetermined part of the revolution of the cutting-cylinders, substantially as described. 30

31. The combination of the continuously-driven feed-rolls, a gear adapted to be driven therewith, means for varying the speed of 40 said rolls, and continuously-driven cutting-cylinders; with a looping-frame adapted to be operated by said gear, and mechanism substantially as described, whereby said gear is caused to intermittently move the looping-frame during a predetermined part of the revolution of the cutting-cylinders, irrespective of the speed of the feed-rolls, substantially as described. 45

In testimony that I claim the foregoing as 50 my own I affix my signature in presence of two witnesses.
